CLAIM

The ornamental design for an electrical insulator with integral current sensor, as shown and described.

DESCRIPTION

FIG. 1 is a perspective view of an electrical insulator with integral current sensor showing our new design; FIG. 2 is a front elevational view thereof; FIG. 3 is a rear elevational view thereof; FIG. 4 is a left side elevational view thereof, the right side elevational view being a mirror image; FIG. 5 is a top plan view thereof; FIG. 6 is a bottom plan view thereof.

FIG.1

FIG.2

FIG.3

FIG. 4

FIG. 5

FIG. 6
